(57) **CLAIM**

The ornamental design for a pedal assembly for rhythmic movement training, as shown and described.

DESCRIPTION

FIG. 1 is a perspective view of a pedal assembly for rhythmic movement training showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are included for illustrating unclaimed portions of the pedal assembly for rhythmic movement training and form no part of the claimed design.

1 Claim, 7 Drawing Sheets
